DEVICE FOR THE REPRODUCTION OF SOUND

Application filed February 28, 1929. Serial No. 343,424.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

This invention relates to devices for the reproduction of sound, but more particularly to radio loud speakers and the like, and has for its object to provide certain improvements in this class of devices.

In speakers having the type of diaphragm to which this invention is particularly, though not necessarily directed, I have found that the same are well suited for the application of a plurality of diaphragm driving or actuating units, and this type of diaphragm will therefore be employed as illustrating the invention, though it is to be understood that the system may be applied to or used in connection with any suitable diaphragm forms or constructions.

20 A speaker diaphragm properly designed proportioned and constructed when connected to an efficient actuating unit will faithfully reproduce both high and low frequencies without favoring either, that is to say without accentuating either the highs or the lows, nor slighting either the highs or the lows.

Speakers therefore as usually constructed have their own peculiar characteristics and 30 are capable, of course, of accommodating themselves to a considerable range in volume under the influence of the "volume control" with which all modern receiving sets are equipped. This flexibility in volume, however, is simply a product of the amplitude of the impulses imparted to the diaphragm; the greater the amplitude the greater the volume. The quality or the characteristics of the sound reproduced is not thereby influenced, or to be more correct, is not intended to be changed or influenced by variations in the amplitude of the impulses imparted to the diaphragm under the influence of the "volume control" of the receiving set. As a matter of fact rattling and distortion may be the result of too great volume and thus the quality and characteristics of the sound may be effected by amplitude or volume. But such change in 50 quality and characteristics of the sound re-

produced is of no concern here, and the term "quality and characteristic" of sound whenever appearing in the specification and the claims will have no reference to such imperfections as may spring from too great amplitude delivered to the speaker by the receiving set under the influence of the "volume control" thereof.

This invention therefore has for its object to provide a drive system for the diaphragms of speakers whereby the quality and characteristics of the sound produced by the diaphragm may be changed, modified or altered. As one particular example of such change in the quality or characteristic of the sound produced by the diaphragm, I am enabled at any given volume-setting of the receiver to control the loud speaker, so that the normal reproduction may be changed at will to accentuate the high and moderate frequencies, 60 sharpen the definition, eliminate overtones and resonance and practically eliminate the lows, or at any given volume setting of the receiver to improve the detail of the reproduction, enhance the sensitiveness of the loud speaker, reproduce the overtones and natural 65 resonance and give full value to the lows.

Thus the system is particularly applicable to the reproduction of speech where sharpness of definition of the spoken words is desirable and the accentuation of moderate frequencies to the exclusion of fuzziness, overtones and resonance is materially advantageous. And the system is equally applicable to the reproduction of sound generally such as musical and vocal programs where volume is 70 desirable and sensitiveness, detail, overtones, natural resonance, and full value to the lows are necessary to faithful reproduction.

The invention in its broadest aspect has for 75 its inventive purpose to deliver, by means of suitable instrumentalities at one point or location in the air sound producing impulses, and to deliver at a different but adjacent point or location in the air like sound producing impulses, the positive impulses or impulses of compression delivered at the one point or location in the air being accompanied by simultaneous negative impulses or impulses of rarefaction delivered at the different but adjacent 80

point or location in the air, to the end that the audible sounds created by the high and moderate frequency impulses are sharpened and their definition improved, while the audibility of the sounds created by the low frequency impulses is impaired, and fuzziness, overtones and resonance eliminated.

Likewise the invention in a more limited aspect has for its inventive purpose the accomplishment of the above stated result, and in addition thereto, the provision of means for causing said instrumentalities to deliver at different but adjacent points or location in the air like sound producing impulses, the positive and negative impulses or impulses of compression and rarification produced at the one point or location in the air being accompanied by simultaneous positive and negative impulses or impulses of compression and rarification delivered at the different but adjacent point in the air, to the end that the audibility of the sounds created by the low frequency impulses is unimpaired, and the same together with the overtones and natural resonance of the reproduced sounds are present at their normal value.

The drawing is simply illustrative of a preferred arrangement of parts for carrying out my inventive purpose, and since other arrangements and instrumentalities may be employed for producing a like result, I consider all such modifications, changes, alterations and variations to be within the spirit of this invention when falling within the limit and scope of the appended claims.

Referring to the accompanying drawing—

Figure 1 is a front elevation of a preferred form of the invention;

Figure 2 is a side elevation of the same;

Figure 3 is a rear elevation of the same;

Figure 4 is a top plan view of the same;

Figure 5 is a vertical longitudinal sectional view through the same;

Figure 6 is a diagrammatic view of one form of diaphragm actuating system illustrating the electrical circuits thereof;

Figure 7 is a diagrammatic view of the system illustrating in full lines the circuit employed for normally actuating the diaphragm by one motor;

Figure 8 is a similar view of the system illustrating the electrical circuit for actuating the diaphragm by a plurality of motors connected in parallel; and

Figure 9 is a similar view of the system illustrating the electrical circuit for actuating the diaphragm by the motors connected in reverse parallel.

For the purpose of illustrating the invention only two motors have been shown though it is obvious that any number of actuating motors may be employed and may be arranged or connected with the diaphragm in any manner best suited to the size, shape and

construction of the diaphragm or to meet any particular conditions.

Referring to the drawings by reference numerals:

1 indicates the speaker, which in the example shown includes a driven diaphragm 2, frame 3, and actuating motors 4 and 5.

The diaphragm is suitably mounted on its frame 3, which may also serve as a mounting for the motors 4 and 5, which may be suitably connected to the diaphragm 2 at the points 6 and 7.

R indicates a radio receiving set of any type to which the lowermost motor 5 is electrically connected by the wires 8 and 9, and is the source of the sound producing pulsating current. This is indicated as the circuit A.

10 indicates a double throw double pole knife switch and 11 and 12 indicate the poles of the switch knife 13. The motor 5 is also connected to the switch-knife poles 11 and 12 by the wires 8 and 9.

The uppermost motor 4 is connected to the two poles 14 and 15 of the switch 10 by wires 14' and 15' so that when the switch is thrown to connect said poles 11 and 12 of the knife 13, the two motors 4 and 5 are connected in parallel. This is indicated as the circuit B.

Connecting the motor 4 with the other two poles 16 and 17 of the switch are two wires 18 and 19, and said wires are crossed so that they respectively pass to said switch poles 16 and 17 on the sides opposite and reverse to those to which the wires 14' and 15' are connected. When the switch knife 13 is thrown to connect said poles 16 and 17 with the poles 11 and 12 of the switch knife 13, the two motors 4 and 5 are connected in reverse parallel, which changes the direction of flow of the pulsating current to the unit 4.

The foregoing system produces the following results.

When the diaphragm is being actuated by the motor 5 alone in the circuit A, the diaphragm is receiving the full impulses from said motor and normal action of the diaphragm and consequently normal reproduction results. This is of course obtained when the switch knife 13 is in raised or neutral position.

When the switch knife 13 is thrown to connect with the switch poles 14 and 15, the diaphragm is then actuated at two different points by the motors in the circuit B, which motors being connected in parallel in said circuit impress their impulses at two points to the diaphragm in unison so that both motors deliver positive impulses simultaneously and negative impulses simultaneously. The result is that the energy which the two motors 4 and 5 jointly receive from the receiving set is the same as the single motor 5 receives when operating alone in circuit A, and nothing in energy is gained. The acoustical result however is that in the case of the two

5 motors operating in circuit B, the impulses from the two motors being delivered at two points along the diaphragm causes a more complete vibration throughout the entire diaphragm structure resulting in an increased volume, greater sensitiveness and detail and a consequent improvement in the value of the 10 lows.

With the motors 4 and 5 connected in parallel in the circuit B, the energy delivered to each motor in the circuit is exactly one-half of that delivered to the single motor 5 in circuit A, for any given setting of "volume control" of the receiver. Likewise the 15 amplitude of the impulses of the two motors is exactly one half of the amplitude of the impulses of the single motor when operating alone. In consequence, the two motors in circuit B are capable of receiving and utilizing twice the energy of the single motor in circuit A, so that the sum of the amplitudes of the impulses of the two motors in circuit B will in that case be twice that of the single motor 5 in circuit A. Consequently the two motors 4 and 5 in circuit 20 B may increase by a multiple of 2 the volume of sound reproduced by the diaphragm over the maximum limit of the single motor 5 in circuit A.

30 What is said in the foregoing paragraph has equal application to the motors when connected in circuit C, when the switch knife 13 is thrown to connect with the switch poles 16 and 17. But in this case an entirely different diaphragm action and acoustical phenomena result. The direction of the flow of current to one of the motors being thus reversed in this circuit, the impulses delivered to and impressed upon the diaphragm by the 35 motors are exactly opposed. A positive impulse from the motor 4 is impressed at one point of the diaphragm simultaneous with a negative impulse impressed by the motor 5 at a different point on the diaphragm, and a 40 wave of compression is imparted to the air by the upper portion of the diaphragm simultaneously accompanied by a wave of rarefaction from the lower portion of the diaphragm in the same direction as the wave 45 of compression.

50 The result of this action in a properly designed and proportioned diaphragm is to accentuate the high and moderate frequencies, sharpen the definition thereof, relieve 55 the reproduced sound from all fuzziness, overtones and resonance and practically eliminate the lows. In fact low frequencies of slight amplitude which are plainly and audibly reproduced by the diaphragm when 60 actuated under the circuits A and B are entirely inaudible under circuit C. In consequence the high and moderate frequencies reproduced by the diaphragm under circuit C are clarified, refined and sharpened in definition to the end that the actuation of the dia-

phragm under circuit C is particularly applicable to the reproduction of speech.

65 In order that those skilled in the art may be able to make and use the invention without experimentation, it may be stated that the diaphragm in the example shown in the drawing and herein described is of the shape and formation illustrated, and when flexed in that formation is 22½ inches high, 11½ inches from front to back and 18 inches wide.

70 These dimensions however are not critical and are only stated by way of description and not by way of limitation, as I do not consider myself limited to any size, shape or formation of diaphragm, nor to any particular number or location of actuating motors nor to any particular circuits, but consider myself clearly entitled to all changes, alterations, modifications and all instrumentalities 75 whatsoever as may fall within the limit and scope of the appended claims.

80 I claim—

1. A device for reproducing sound including a diaphragm, a plurality of diaphragm actuating units for impressing sound producing impulses on the diaphragm at different points thereon, an electrical circuit for two of the actuating units to cause the two units to impress like positive sound producing impulses on the diaphragm simultaneously at 90 two different points on the diaphragm, an electrical circuit for the two actuating units to reverse the direction of flow of the pulsating current to one of the units with respect to the other of the units, to cause one of the units to impress positive sound producing 95 impulses at one point on the diaphragm and to cause the other unit to simultaneously impress negative sound producing impulses at another point on the diaphragm, and an electrical switch for connecting the two units in either of the two circuits.

100 2. A device for reproducing sound, including driven means for delivering sound producing impulses to the air, a plurality of driving devices for impressing simultaneous positive and negative sound producing pulsations to the driven sound producing means at different but adjacent points in the air, whereby the positive sound producing 105 impulses delivered at one point in the air are accompanied by simultaneous negative sound producing impulses delivered at a different but adjacent point in the air, to the end that the audibility of low frequency sound producing impulses is impaired, the definition of moderate and high frequency sound producing impulses sharpened, and resonance and overtones eliminated.

110 3. A device for reproducing sound, including driven means for delivering sound producing impulses to the air, a plurality of driving devices for impressing simultaneous positive and negative sound producing pulsations to the driven sound producing means 115 120 125 130

at different but adjacent points in the air, whereby the positive sound producing impulses delivered at one point in the air are accompanied by simultaneous negative sound producing impulses delivered at a different 5 but adjacent point in the air, to the end that the audibility of low frequency sound producing impulses is impaired, the definition of moderate and high frequency sound producing impulses sharpened, and resonance and overtones eliminated, and means for controlling the driving pulsation-impressing devices to impress positive sound producing pulsations simultaneously and negative sound producing pulsations simultaneously on the sound producing means at different but adjacent points in the air, whereby the positive and negative sound producing impulses delivered at one point in the air are simultaneously 10 accompanied by like positive and negative sound producing impulses delivered at a different but adjacent point in the air, to the end that the audibility of low frequency sound producing impulses are unimpaired and resonance and overtones reproduced at their true values.

4. A device for reproducing sound for use in connection with a source of sound producing pulsating current, including a diaphragm, a plurality of diaphragm actuating units for impressing sound producing pulsation to the diaphragm at different points thereon, two electrical circuits for the diaphragm actuating units, in one of which circuits the pulsating current flows in the same direction to the diaphragm actuating units, in the other of the circuits the direction of flow of the pulsating current to one of the diaphragm actuating units is reversed, whereby in the latter circuit the diaphragm actuating units impress positive sound producing pulsations simultaneously with negative sound producing pulsations on the diaphragm at different points thereon, and means for connecting the units in either of the two circuits.

5. A device for reproducing sound for use in connection with a source of sound producing pulsating current, including a diaphragm, a plurality of diaphragm actuating units for impressing sound producing pulsations at different points thereon, an electrical circuit for the diaphragm actuating units in which circuit the direction of flow of the pulsating current to one of the diaphragm actuating units is reversed, whereby the diaphragm actuating units impress positive sound producing pulsations on the diaphragm at one point and simultaneously impress negative sound producing pulsations on the diaphragm at a different point thereon.

6. A device for reproducing sound for use in connection with a source of pulsating sound producing current, including a diaphragm, a plurality of diaphragm actuating units,

means for electrically connecting the diaphragm actuating units together to cause the same to impress sound producing impulses in unison on the diaphragm at different points thereon, and for electrically connecting the diaphragm actuating units together to cause the same to impress opposed sound producing impulses on the diaphragm at said different points thereon.

7. A device for reproducing sound including a diaphragm, a plurality of diaphragm actuating units connected to the diaphragm at different points thereon, means for electrically connecting the units together for pulsating said different points of the diaphragm together and in unison, and for electrically connecting the units together for pulsating the said different points of the diaphragm together but in opposition.

8. A device for reproducing sound including a diaphragm, a plurality of diaphragm actuating units connected to the diaphragm at different points thereon, and means for electrically connecting the units together for pulsating the said different points of the diaphragm together but in direct opposition.

9. A device for reproducing sound including a diaphragm, a plurality of diaphragm actuating units connected to the diaphragm at different points thereon, and an electrical circuit for the units in which they are energized to pulsate said different points of the diaphragm together but in direct opposition.

10. A device for reproducing sound including a diaphragm, means for pulsating different points of the diaphragm together and in unison and for pulsating said different points of the diaphragm together, but in direct opposition, and means for controlling the diaphragm pulsating means to pulsate the diaphragm in unison or in direct opposition.

11. A device for reproducing sound for use in connection with a source of sound producing pulsating current, including a vibratory diaphragm, a plurality of diaphragm actuating units connected to said diaphragm at different points thereon, a plurality of electrical circuits for said actuating units, in one of which circuits the pulsating current flows to the actuating units in the same direction, in another of said circuits the direction of flow of the pulsating current to one of the units is reversed with respect to another of the units, whereby in one of the said circuits the whole diaphragm is pulsated by the units to deliver alternate positive and negative impulses, while in another of the said circuits the diaphragm is pulsated by the units to deliver positive and negative impulses simultaneously, and means for connecting the units in either of the said circuits.

12. A device for reproducing sound including a diaphragm, means for actuating the diaphragm for delivering positive and negative impulses alternately and for actuating

the diaphragm for delivering positive and negative impulses simultaneously, and means for selectively controlling the said diaphragm actuating means to cause the diaphragm to deliver either positive and negative impulses alternately, or positive and negative impulses simultaneously.

In testimony whereof I affix my signature.

CHARLES HUGH DUFFY.
